Emil Weichert

UNITED STATES PATENT OFFICE.

EMIL WEICHERT, OF AUGSBURG, GERMANY.

APPARATUS FOR THE ELECTROLYSIS OF FLUIDS.

No. 896,184.

Specification of Letters Patent.

Patented Aug. 18, 1908.

Application filed October 24, 1906, Serial No. 340,364. Renewed May 11, 1908. Serial No. 432,276.

To all whom it may concern:

Be it known that I, EMIL WEICHERT, a subject of the German Emperor, and resident of Hartmannstrasse 6, Augsburg, Germany, 5 have invented certain new and useful Improvements in Apparatus for the Electrolysis of Fluids, of which the following is a specification.

The invention relates to an apparatus for 10 the electrolytic treatment of fluids, which is specially adapted for the production of bleach liquors, and has for its object first to increase the product for the electrical energy expended, and further to produce a greater 15 yield from the raw material such as salt used.

It is well known that bleach liquors on account of their strong corrosive action can only be manufactured in vessels made of certain materials, and that during the electrolysis the electrolyte itself is strongly heated. 20 Care has therefore to be taken in the manufacture of such vessels to make use of the cheapest materials which can be used such as clay or burned alumina, and during the electrolytic process to cool the electrolyte.

In the present invention the desired object is attained by leading the electrolyte through a cooled coil made from clay arranged horizontally and situated in a cooling chamber. 30 The upper parts of the windings discharge into chambers in which the electrodes are so arranged that each chamber has a positive and a negative pole. Each winding of the cooling coil joins two chambers, so that the solution 35 enters the first chamber and is here electrolytically treated, and then passes through the first winding of the coil being at the same time cooled and enters the second electrolytic chamber, where it is again submitted to electrolysis. The solution next passes through 40 the second winding of the coil and is thereby again cooled and then enters the third electrolytic chamber. And so the process of electrolysis and cooling is alternately repeated 45 until the liquid has passed through all the chambers and all the windings. The number and size of electrolytic chambers and the dimensions of the coil windings depend upon the 50 quantity of fluid to be treated and the electric energy available.

By means of the present invention it is possible with a comparatively small apparatus when the electrolyte is sufficiently cooled to produce an especially high in fact any desired 55 concentration of electrolyzed liquor without passing the fluid several times

through one apparatus or consecutively through several apparatuses.

In the drawing two forms of construction of the new apparatus are shown.

Figure 1 is a side view of the apparatus shown partially in section; Fig. 2 is an end view of the same showing the circular form of a winding of the coil, the outer cooling vessel being shown in section, Fig. 3 shows a 60 partial longitudinal section on line I—I of Fig. 5. Fig. 4 is a section on line II—II of Fig. 5 showing that the cooling coil can also possess angular windings. Fig. 5 is a plan of the apparatus. Fig. 6 is a side view of the 65 spiral coil itself shown partly in section. Figs. 7 and 8 show top and lateral views respectively of a form of construction of an electrode carrier. Figs. 9 and 10 show another arrangement of the electrodes on the 70 electrode carrier.

In Figs. 1—6. 1 is the cooling coil lying in the cooling chamber 2 whose windings a, b, c, d, . . . discharge above into the chambers g, h, i, k, . . . the winding a connecting 80 chambers g and h and the winding b connecting chambers h and i and so on. The chambers g, h, i, k, are formed by the division of a trough 3 (Figs. 3, 5, 6) by means of partitions 4 into the required number of compartments 85 g, h, i, k, . . . In this way a stable connection of the coil windings a, b, c, d, . . . is attained, and a suitable support for the coil. This is especially important, because it is thereby possible to shape the complete coil which as 90 stated above is made from clay, sufficiently strong for the burning in the furnace. In the chambers g, h, i, k, . . . the electrodes are so arranged that each chamber has a positive and a negative pole.

As carrier for the electrodes use is made of such an apparatus as suits the particular case, examples are shown in Figs. 7 and 8 or 9 and 10 respectively. The bent carrier 4 consisting of suitable conducting material has at its 100 bend one or more feet 5 and at the end of the two arms feet 6 and 7. The carrier 4 has also holders 8 for the electrodes 9; the latter can be made from any material suitable for the purpose and may be manufactured in any 105 suitable form. For instance electrodes of hardened lead with a core of copper, or electrodes of platinum or carbon can be used.

The carrier 4 rests with its feet 5, 6, 7, in notches 10 in the upper edge of the cooling 110 vessel and the feet 5, 6, 7 are so long that the carrier 4 is completely out of contact with the

partitions 3 and therefore the chambers *y, h, i, k, . . .* The electrodes supported by the one arm forming for instance the positive pole dip into the solution of the one chamber, 5 while the electrodes supported by the other arm forming the negative pole dip into the solution of the next chamber.

The electrodes can stand either at right angles to the arms as shown in Figs. 7 and 8, 10 or parallel to the same as in Figs. 9 and 10.

The operation of the new apparatus proceeds as follows: The fluid enters from a tank 12 (Fig. 6) provided with a regulating cock 11 into the intermediate vessel 13, and from 15 here into the first chamber *g*. The fluid proceeds as shown in Fig. 5 in the direction of the arrow and meets the first pair of electrodes and is here subjected to electrolysis. At the opposite end of the chamber *g* to the 20 inlet for the fluid is the inlet to the first winding *a*. The fluid falls into this winding *a* fills the same, rises high, and enters the second chamber *h*. Here it is again subjected to electrolysis, and then falls into the winding 25 *b*, fills it and enters the third chamber *i*, and so on until it reaches the outlet 14. According to the voltage available any desired 30 number of cells can be connected up in series. Experience shows that the best results are produced when the voltage lies between $3\frac{1}{2}$ and 4 volts per cell, and therefore such a disposal of the current should be made as will permit this to exist. Each electrode 35 may consist of a single plate, or a plurality of plates as desired.

It may be added that the construction of the trough 3 or the form of the cooling coil may be modified without leaving the scope of the invention.

40 The individual electrode carriers or electrodes may also have other forms, as stated above.

What I claim as my invention and desire to secure by Letters Patent is:—

45 1. In an apparatus for the electrolysis of fluids the combination of a tubular coil arranged so that its axis is horizontal said coil being made of suitable material and adapted to conduct the fluid, chambers made of suitable material at the top of each winding of the coil, said chambers containing the outlet of one winding and the inlet of the next, electrodes in each of the said chambers, means to support the electrodes, a cooling 50 vessel suitable for the reception of the coil,

and means to regulate the flow of fluid through the series, all substantially as set forth.

2. In an apparatus for the electrolysis of fluids the combination of a tubular coil arranged so that its axis is horizontal said coil being made of suitable material for conducting the fluid, a trough arranged over the coil, partitions for dividing the trough into compartments, each compartment containing the inlet of one winding and outlet of the next, a positive electrode and a negative electrode in each compartment, means for supporting said electrodes in the fluid to be electrolyzed, means for regulating the flow of fluid through the series, and a cooling vessel inclosing the tubular coil substantially as set forth.

3. In an apparatus for the electrolysis of fluids, the combination of a tubular coil arranged so that its axis is horizontal, said coil comprising a number of tubular windings of circular shape, an electrolytic cell at the top of each tubular winding into which the same discharges, electrodes in said cells, a carrier for the electrodes composed of suitable conducting material, and a cooling vessel surrounding the said tubular coil substantially as set forth.

4. In an apparatus for the electrolysis of fluids, the combination of a tubular coil arranged so that its axis is horizontal comprising a number of tubular windings of an angular shape, each winding discharging at the top into an electrolytic cell, an electrolytic cell at the top of each winding, a positive and negative element in each electrolytic cell, a carrier for the electrodes, provided with feet standing in grooves on the sides of the outer cooling vessel, said carrier being adapted to stand over two adjacent cells supporting a cathode in the one and an anode in the other, means for regulating the flow of fluid, and an outer vessel adapted to contain a refrigerating material adapted to cool the liquid when flowing through the coil substantially as set forth.

In testimony whereof I have hereunto signed my name this third day of October 1906, in the presence of two subscribing witnesses.

EMIL WEICHERT.
